UNITED STATES PATENT OFFICE.

CHARLES T. BLOOMER, OF NEWARK, NEW YORK.

PAPER RECEPTACLE.

No. 902,932.

Specification of Letters Patent.

Patented Nov. 3, 1908.

Application filed August 9, 1906. Serial No. 329,921.

To all whom it may concern:

Be it known that I, CHARLES T. BLOOMER, a citizen of the United States, residing at Newark, in the county of Wayne and State 5 of New York, have invented a new and useful Paper Receptacle, of which the following is a specification.

This invention relates to paper receptacles and more particularly to that class of receptacles especially designed for carrying 10 oysters and other liquid or semi-liquid substances.

The object of the invention is to provide a pail or receptacle the side walls of which 15 are extended above the fold lines at the top of the pail thereby to form a water-tight closure for the pail and effectually prevent the liquid from slopping over the side walls and escaping at the cover.

20 A further object is to provide a pail having rectangular side panels the free ends of which are adapted to be folded downwardly on top of the cover when the latter is closed thus reinforcing and strengthening the cover 25 and at the same time preventing leakage of the contents of the pail.

30 A further object is to provide a supporting bail the terminals of which pierce the opposite sides of the pail and terminate short of the inner walls thereof.

35 A still further object of the invention is to generally improve this class of devices so as to increase their utility, durability and efficiency.

40 Further objects and advantages will appear in the following description, it being understood that various changes in form, proportions and minor details of construction may be resorted to within the scope of the appended claims.

45 In the accompanying drawings forming a part of this specification: Figure 1 is a perspective view of an oyster-pail or receptacle constructed in accordance with my invention. Fig. 2 is a transverse sectional view of the same. Fig. 3 is a similar view taken at right angles to Fig. 2 and showing the cover in open position. Fig. 4 is a perspective view showing the cover partially closed. 50 Fig. 5 is a plan view of the blank from which the pail or receptacle is formed. Fig. 6 is a perspective view partly in section illustrating a modified form of the invention.

55 Similar numerals of reference indicate corresponding parts in all of the figures of the drawings.

The improved pail or receptacle is preferably formed from a paper, or card-board blank of the construction shown in Fig. 5 of the drawings, and consists of a bottom-section 5 having converging side and end walls or sections 6 and 7, connected by corner-folds 9 and 10, the side walls 7 being provided with substantially rectangular panels 8, as shown. 60

The end walls 6 are provided with lateral extensions 11 which form the top or cover of the pail when the blank is folded, said extensions being connected with the adjacent corner-folds 9 and 10 by auxiliary folds 12 70 and 13 which together with the extensions 11 constitute the top or cover of the receptacle.

The opposite longitudinal edges of the panels 8 are arranged parallel with each other and the free ends of said panels extended 75 laterally beyond the adjacent end of the blank and inclined or beveled in opposite directions to form side flaps 14 adapted to overlap the corner-folds 13 of the cover thereby to reinforce and strengthen the cover 80 at the point of attachment of the fastening devices 15 and 16.

Attention is here called to the fact that the edges of the corner-folds 10 and panels 8 are extended beyond the fold lines 17 to provide a flap 17^x, which when the blank is folded to form the vessel and the cover of the latter moved to closed position the panels 8 will project inwardly over the cover, as shown, in Fig. 2 of the drawings thereby 90 forming a water-tight closure and effectually preventing the liquid from slopping over the side walls and leaking at said cover.

It will also be observed that by reason of the shape of the panels 8 the blank may be 95 conveniently folded without the necessity of severing any portion of the blank or folding extra stock at the corners of the pail which is the case where the side walls are inclined or tapered.

100 The fastening device 16 consists of a clip one end of which pierces the adjacent extension 14 and the corner-folds 13 while the opposite end thereof is bent to form a hook 17^x adapted to engage the loop of the fastening device 15, the latter being preferably formed of a single length of wire the ends of which are extended through the flap 14 and corner-folds 13 on the opposite side of the box, as 105 shown.

110 It will thus be seen that the fastening devices serve to retain the flaps 14 and corner-

2
folds 13 in assembled position and also serve to secure the cover in closed position.

As a means for supporting the vessel when transporting the latter from place to place there is provided a suitable handle or bail 18 preferably formed of a single piece of wire the opposite ends of which are bent to form terminal points 19 which pierce the reinforced side walls of the receptacle and terminate short of the interior walls of the latter thus presenting a smooth uninterrupted surface for contact with the oysters or other contents of the vessel.

In assembling the pail the side walls 7 are folded inwardly on the lines 20 and the corner-folds 10 folded on the lines 21 and thence folded laterally on the panels 8 so as to present a receptacle similar to that shown in Fig. 3 of the drawings. The oysters or other liquid or semi-liquid substance is then introduced into the receptacle and the cover-extensions 11 folded downwardly on the lines 22, after which the flaps 14 and folds 12 are folded laterally and downwardly in engagement with the upper surface of the extensions 11, as best shown in Fig. 2 of the drawings thus preventing the contents of the vessel from slopping over the side walls and escaping at the top or cover of the pail.

If desired the flaps 14 may be glued, pasted or otherwise secured to the folds 13 before the attachment of the fastening devices 15 and 16 and the bail 18 instead of being formed of wire may be constructed from a single length of water-proof material.

It will here be observed that by folding the receptacle in the manner before described the side walls of the latter are reinforced and strengthened at the points of attachment of the supporting bail while at the same time the extensions 14 of the panels serve to assist in locking the cover in closed position.

In Fig. 6 of the drawings there is illustrated a modified form of the invention in which the side walls or panels 8' terminate short of the adjacent ends of the folds or flaps 13 when the blank is folded, the severed portion being indicated by the dot and dash line 23 in the blank shown in Fig. 5 of the drawings. In this form of the device the free ends of the side walls or panels 8' extend a short distance above the fold lines 17 and are secured in any suitable manner to the folds 13 as by staples 24, the extended portion 25 of the pail being foldable downwardly into engagement with the adjacent surface of the cover when the latter is closed so as to prevent leakage in the manner before described.

The boxes may be made in different sizes and shapes and formed of paper or other suitable material capable of being bent into the desired shape.

From the foregoing description it is thought that the construction and operation of the device will be readily understood by those skilled in the art and further description thereof is deemed unnecessary.

Having thus described the invention what is claimed is:

1. A paper receptacle including a body portion provided with an integral cover and having some of its vertical walls provided with substantially rectangular panels reinforced by over-lapping wings foldable laterally in engagement with the exterior walls of the panels, there being fold lines disposed at the juncture of the cover and vertical walls of the receptacle, the opposite longitudinal edges of the panels being disposed parallel and extended upwardly in parallel relation to a point beyond the adjacent fold lines for engagement with the top of the cover when the latter is closed.

2. A paper receptacle including a body portion formed with an integral cover and having some of its vertical walls provided with substantially rectangular panels reinforced by over-lapping wings foldable laterally in engagement with the exterior walls of the panels, there being fold lines disposed at the juncture of the cover and vertical walls of the receptacle, the opposite longitudinal edges of the panels being disposed parallel and extended upwardly in parallel relation to a point beyond the adjacent fold lines and thence inclined towards the free ends of the adjacent cover sections and terminating flush therewith, said panel extensions being foldable downwardly on the cover when the latter is closed.

3. A paper receptacle having converging side and end walls, the side walls being provided with rectangular panels and reinforced by over-lapping wings foldable laterally in engagement with the exterior walls of the panels, said receptacle being provided with an integral cover and having fold lines disposed at the juncture of the cover and vertical walls of the receptacle, the opposite longitudinal edges of the panels being disposed parallel and extended upwardly in parallel relation to a point beyond the adjacent fold lines for engagement with the top of the cover when the latter is closed.

4. A paper receptacle including a body portion provided with an integral cover and having some of its vertical walls provided with substantially rectangular panels reinforced by over-lapping wings foldably laterally in engagement with the exterior walls of the panels, there being fold lines disposed at the juncture of the cover and vertical walls of the receptacle, the opposite longitudinal edges of the panels being disposed parallel and extended upwardly in parallel relation to a point beyond the adjacent fold lines for engagement with the

top of the cover when the latter is closed, and a supporting bail having its opposite ends piercing the vertical walls of the receptacle and the adjacent reinforcing panels beneath said fold lines.

5. A paper receptacle having converging side and end walls, the side walls being provided with substantially rectangular panels reinforced by over-lapping wings foldable laterally in engagement with the exterior walls of said panels, said receptacle being provided with an integral cover and having fold lines disposed at the juncture of the cover and vertical walls of the receptacle, 10 the opposite longitudinal edges of the panel being disposed parallel and extended upwardly in parallel relation to a point beyond the adjacent fold lines and thence inclined upwardly on converging lines to produce vertical extensions, fastening devices 15 piercing the panel extensions and adjacent cover sections for locking the cover in closed position, and a supporting bail having its opposite ends extended through the vertical walls of the receptacle and the adjacent reinforcing panels beneath the cover fold lines.
6. A blank for paper vessels comprising a body portion provided with a plurality of fold-lines defining a bottom-section and 20 radiating side and end sections, the end sections being inclined and the side sections having their opposite longitudinal edges parallel and provided with terminal flaps extending laterally on converging lines

beyond the opposite longitudinal edges of 35 the blank, there being corner-walls connecting the side and end sections, and cover-sections extending laterally from the end-sections and connected with the corner-folds, there being a fold-line spaced inwardly from 40 the opposite longitudinal edges of the blank and connecting the corner-folds on each side thereof.

7. A blank for paper boxes comprising a body portion having parallel longitudinal 45 edges and provided with a bottom section having inclined end sections and parallel side sections radiating therefrom and defining fold-lines, the side sections being provided with terminal flaps extended laterally 50 on converging lines beyond the adjacent longitudinal edges of the blank there being corner-folds disposed between the end and side sections, cover-sections extending laterally from the end sections of the blank and 55 connected with the corner-folds by auxiliary folds, there being a fold-line extending inwardly from the opposite longitudinal edges of the blank and connecting the corner-folds, said fold line intersecting the side 60 sections of the blank.

In testimony that I claim the foregoing as my own, I have hereto affixed my signature in the presence of two witnesses.

CHARLES T. BLOOMER.
